PROCESS FOR TREATING GASES

Application filed June 27, 1927. Serial No. 201,728.

The present invention relates to the treatment of gases and more specifically comprises a process for extracting gasoline from hydrocarbon gases. Our invention will be fully understood from the following description and the drawing which illustrates one form of apparatus for carrying out our process.

The drawing represents in diagrammatic form an apparatus built according to our invention and indicates the flow of gas through the apparatus.

In petroleum refineries where petroleum oil is subjected to different kinds of treatment, such as ordinary distillation processes and cracking processes, large volumes of gas are obtained, and part of this gas is generally used as fuel at the refinery. Gas from pressure stills or other forms of cracking equipment is generally obtained at pressures above atmospheric, often from 50 to 100 pounds per square inch or higher, while the gas from crude or rerun stills is generally at low pressure and sometimes even at sub-atmospheric pressures. The gas from both of these sources contains more or less gasoline and it is customary to recover the gasoline by compression, oil absorption, or adsorption on activated charcoal, as is well known in the art. In the present invention gas at a high pressure is utilized to compress low pressure still gas in such a manner that gasoline is condensed from either or both gases which are then mixed at a common intermediate pressure. The last traces of gasoline are preferably removed from the gas before discharge to the boilers or stills as fuel.

Referring to the drawing, the reference character A indicates generally a compressor of any approved type but which is shown as a single stage piston compressor of the kind generally in use for compressing air. The cylinders 1 and 2 are the "steam" and "air" cylinders respectively and are placed in alignment, with a single piston rod 3 fitted with pistons 4 and 5 in the cylinders 1 and 2. The cylinders are provided with slide valves 6 and 7 of any preferred type, as will be understood.

High pressure gas from any convenient source is fed to cylinder 1 by pipe 8. Such

source may be a pressure still or preferably one or more batteries of such stills, (not shown). The expanded gas leaves the cylinder by line 9 and is discharged to a gas separator drum 10 by line 11. Low pressure still gas is fed to the compression cylinder 2 by line 12 and is discharged through line 13 and cooler 14 into the separator 10, where the condensed gasoline is separated and drawn off to tank 15 by a line 16. The gas in drum 10 is under pressure intermediate between the pressures of the original gases, preferably about 30 lbs. per sq. in. gage and at a temperature below that of either of the original gases.

The gas is removed from the drum 10 by a line 17 to a recovery system generally indicated by the reference character B. The high pressure gas may be of such character that no gasoline is produced in the expansion, and in this case it is desirable to by-pass the drum 10 by the line 9*, as will be understood, but in any case the gases from the high and low pressure sources are mixed and flow by line 18 to the final recovery system B.

The final recovery system may be either an oil absorption system as is illustrated, or a system making use of activated charcoal, as will be understood. The mixed gas, preferably at a pressure of 30 lbs. per sq. in., or higher, and at a temperature below that of either of the original gases, is fed to the bottom of the absorption tower 19. The tower may be of any preferred type and is shown fitted with bubble cap plates. The gas flows upwardly through the tower and escapes by the gas line 20 to be used for fuel under stills or boilers or otherwise as preferred. Fresh oil is admitted to the top of tower 19 by the line 21 and after absorbing the gasoline from the gas is withdrawn from the tower by line 22. The rich oil is then stripped of gasoline by the usual methods of the industry, which need not be described, and is returned to the absorption tower 19. The gasoline recovered from the rich oil may be stored in tank 15 or in other storage as desired.

As an example of our process, 70,000 cu. ft. of gas at a pressure of 90-95 lbs. per sq. in. gage is used to compress 30,000 cu. ft. of still

gas containing approximately 5 gal. per 1,000 cu. ft. of gasoline at practically atmospheric pressure. The expanded gas dropped in temperature to 38° F. and the compressed gas at 6 attains a temperature of 205° F. The compressed gas is then cooled and the mixed gas under pressure of 54.3 lbs. per sq. in. gage assumes a temperature of 50° F. Approximately 100 gals. of gasoline is condensed.

10 In a second example, when about equal quantities of the two gases are used, the final pressure is 35 lbs. per sq. in. gage and the temperature 39° F. A considerable quantity 15 of gasoline is condensed from the gas and is suitable for blending purposes similar to natural gas gasoline.

While our invention has been described particularly in relation to gases from high pressure and low pressure stills, it is applicable to gas from other sources, such as natural 20 gas or coke oven gas, wherever two gases are available at high and lower pressure sources and it is desired to obtain a mixture of the two at an intermediate pressure and a temperature below either of the original gases. 25

Our invention is not to be limited by any theory of the operation or by any example 30 which may be given by way of illustration, but only by the attached claims, in which we wish to claim all novelty inherent in our invention.

We claim:

1. A process for treating gases from high and lower pressure sources for recovery of 35 volatile substances, comprising compressing the low pressure gas by expansion of the high pressure gas, cooling the compressed gas, mixing said gases at an intermediate pressure and removing volatile substances from 40 the mixed gases.

2. A process for treating gases from high and lower pressure sources for recovery of volatile substances, comprising compressing the low pressure gas by expansion of the 45 high pressure gas, cooling the compressed gas, withdrawing the condensed liquid, mixing said gases at an intermediate pressure and removing volatile substances from the mixed gases.

50 3. A process for treating hydrocarbon gases from high and lower pressure sources for obtaining gasoline, comprising compressing the low pressure gas by expansion of the high pressure gas to an intermediate pressure, cooling the compressed gas, mixing said gases at the intermediate pressure and removing the gasoline condensed from the same.

4. A process for treating hydrocarbon 55 gases from high and lower pressure sources for obtaining gasoline therefrom, comprising compressing the lower pressure gas by expansion of the high pressure gas, cooling the compressed gas, withdrawing the condensed gasoline, mixing the compressed gas

and the expanded gas and recovering gasoline from the cooled mixture.

5. A process for recovering gasoline from refinery gases, comprising compressing low pressure still gas by expanding high pressure still gas, cooling the compressed gas, withdrawing condensed gasoline from said gas, withdrawing condensed gasoline from the expanded gas and mixing the residual gases at a pressure intermediate between those of the original gases. 75

6. A process for recovering gasoline from refinery gases, comprising compressing low pressure still gas by expansion of high pressure gas derived from cracking apparatus, cooling the compressed gas, mixing the resulting gases at pressure above atmospheric, separating the gasoline condensed by such treatment and recovering the gasoline remaining in the effluent gas. 80

7. A process for treating gases from relatively high and low pressure sources for recovery of volatile substances, comprising compressing the low pressure gas by expansion of the high pressure gas, cooling the thus compressed gas whereby a condensate is formed, withdrawing the condensate, mixing the gases at a temperature below their initial temperatures, and absorbing the volatile substances from the cooled mixed 90 gases. 95

8. A process for treating gases from relatively high and low pressure sources for recovery of volatile substances, comprising compressing the low pressure gas by expansion of the high pressure gas, cooling the thus compressed gas whereby a condensate is formed, withdrawing the condensate, mixing the gases at a temperature below their initial temperatures and at a pressure intermediate 100 their initial pressures, and absorbing the volatile substances from the cooled mixed gases while maintaining the intermediate pressure. 105
